(57) **CLAIM**

I claim the ornamental design for a car seat alarm kit, as shown and described.

DESCRIPTION

FIG. 1 is a front view of the car seat alarm kit showing my new design.

FIG. 2 is a back view thereof;

FIG. 3 is a left side view thereof;

FIG. 4 is a top plan view thereof;

FIG. 5 is a bottom plan view thereof; and,

FIG. 6 is a perspective view thereof shown in environmental use.

The broken lines shown represent unclaimed subject matter and form no part of the claimed design.
